WARDROBE BAG

Irving B. Matross, Newton Center, and Samuel Matross, Brighton, Mass., assignors to Montrose Manufacturing Company, Incorporated, Boston, Mass., a corporation of Massachusetts

Filed May 21, 1964, Ser. No. 369,121
9 Claims. (Cl. 150—1)

This invention relates to wardrobe bags formed of flexible web material and in particular to wardrobe bags which provide a multiplicity of vertically spaced apart compartments that are accessible from a vertical edge of the bag.

One principal object of the invention is to provide an inexpensive wardrobe bag which can store wardrobe articles in a highly compact relation.

Another object is to provide an improved, extensible wardrobe bag, which, in its relaxed state, occupies virtually no space in a closet, and expands to occupy only so much space as is required by the articles it contains.

Another object is to provide a wardrobe bag having compartments adapted to be extended vertically, as well as laterally, to receive wardrobe articles of various dimensions.

Another object is to provide an extensible wardrobe bag having protrusion-free outer side walls, suitable to be hung in a closet from a rod side by side with clothes, without interfering with the clothes, and also suitable for use as a luggage container.

A further object is to provide accessible and compact moth-proof storage for woolen articles.

A still further principal object of the invention is to provide a wardrobe bag of unique construction, and suitable for being made from transparent plastic.

These objects, and others which in part are obvious and in part will appear herein, are realized through the combination of two outer side wall members of web material each extending along the length of the bag, and a single inner side wall member extending between the outer side wall members. The inner side wall has a running length substantially longer than the corresponding running length of the outer side walls, is configured into a multiplicity of vertically spaced apart special loops, and is secured to the outer side walls alternately between the loops, by transversely, preferably horizontally, extending joints. The special loop configuration is defined in the following way: In the relaxed state the inner side wall extends freely, i.e. without being joined to either outer side wall, from a first transverse joint with one of the other side walls downwardly a first distance thence upwardly a second distance substantially greater than the first distance to a second transverse joint with the other of said outer side walls. From this second transverse joint the inner side wall then extends freely downwardly a third distance less than the second distance, and thence upwardly a fourth distance substantially greater than the third distance to a third transverse joint. The parts of the inner side wall and the corresponding outer side wall lying between the first and third transverse joints define the limits of a first compartment and the part of the inner side wall that extends between the second and third transverse joints forms the bottom of the next above compartment. The two compartments are caused partially to vertically overlap due to the relationship of the third and fourth dimensions.

Preferably, according to the invention, the third distance is substantially less than the difference between the first and second distances to obtain the proper amount of overlap. Furthermore, preferably, the first and third dimensions are equal substantially to the same value and

2

the second and fourth dimensions are equal substantially to four times this value.

While, broadly, the invention may not be so limited, it is preferable, and an important concept of the invention, to have a series of such compartments extend substantially the full length of the bag, and to have the bag of a vertically elongated form, shaped to hang from a closet rod.

Preferably, i.e. for dust proof, moth proof or security reasons, the bag is closed at both vertical edges, which could be accomplished by two zippers where the closet is to be accessible from both edges. But in the usual case, it is preferred to close one edge of the bag permanently, and for this purpose, according to the invention, one vertical edge of the inner side wall is secured to corresponding vertical edges of both outer side walls in a joint extending at least substantially continuously throughout the extent of the inner side wall. The interior of the compartments thus formed are accessible only from the opposite vertical edge of the bag.

10 20 In a construction particularly advantageous for plastic film, the vertical edges of all of the walls are secured to vertical reinforcing strapping members.

25 For a permanently closed vertical edge, it is preferable that all three side members be joined together by a single vertical strapping member, folded, on the outside, over the outside margin of the two outer side walls, while at the vertical edge of the bag through which access is to be had, each of the side walls has its own vertical strapping member. In a zippered construction, the cooperating pair 30 of zipper members are secured respectively to the vertical strapping members on the two outer side walls, and the corresponding edge of the inner side wall is located inwardly thereof.

35 Furthermore in a preferred construction for plastic film each transverse joint between the inner side wall and one of the outer side walls comprises two transverse strapping members, one on the outside of the outer side wall, the other on the side of the inner side wall directed away from said outer side wall with securing means, preferably stitching, though heat-sealing is possible, joining together the two transverse strapping members, and the intervening inner and outer side walls. Preferably, the transverse strapping members, at their ends, are secured to the vertical strapping members of the respective outer side wall 40 to afford further support for the loops.

45 When the wardrobe bag is adapted to hang side-by-side with clothes hanging from hangers on a rod in a closet, and to occupy no more space in the closet than required by the contents in the bag, it is preferably that the outside 50 walls be joined together to form an endless loop, with the location of the joint spaced from the ends of the bag, whereby the ends of the bag are formed by end-folds of continuous side wall material, it being preferred that the inner side wall terminates short of these end folds.

55 To illustrate the foregoing concepts a preferred embodiment is presented in the drawings wherein: FIG. 1 is a vertical side view of one side of a wardrobe bag according to the invention; FIG. 2 is a vertical edge view of the wardrobe bag according to the invention with the bag in a substantially relaxed state, with no articles contained therein; FIG. 3 is a vertical side view of the other side of the embodiment; FIG. 4 is a top view of the bag with one vertical edge open for access to the compartments 60 therein; FIG. 5 is a top view, similar to FIG. 4, with both vertical edges closed; FIGS. 6 and 7 are horizontal cross-sectional views taken on lines 6—6 and 7—7 of FIG. 3, of the vertical edge of the bag through which access may be had, FIG. 7 showing half the bag cross section as opposed to FIG. 6 which shows the entire bag cross section; FIG. 8 is a horizontal cross-sectional view taken on line 65 8—8 of the permanently closed vertical edge of the bag;

70

FIG. 9 is a vertical cross-sectional view similar to the view of FIG. 2, but on a larger scale. FIGS. 10, 11, 12 and 13 are views similar to FIG. 9, but showing the compartments of the bag distended in various ways for receiving contents of various configurations.

Referring to FIGS. 1-3 and 9 the wardrobe bag of this embodiment is of vertical, elongated form, comprised of two uninterrupted outer side walls 20 and 22, capable of lying in parallel planes, and an inner side wall 24. As shown, the inner side wall 24 is configured into a multiplicity of vertically spaced apart special loops, the running length of the inner side wall 24 being substantially longer than the corresponding running lengths of the outer side walls 20 and 22. The inner side wall 24 is secured to the outer side walls alternately between the loops, e.g. at transverse joints 26, 28, 30 and 32.

For the special loop construction, referring particularly to FIG. 9, the inner side wall 24, from a first transverse joint 26 on outer side wall 20, extends freely, i.e. without being joined to either side wall 20 or 22, downwardly a first distance L_1 , thence upwardly a second distance L_2 substantially greater than the first distance L_1 , to a second transverse joint 28 with the other of the outer side walls 22. From this second transverse joint 28, the inner side wall 24 then extends freely downwardly a third distance L_3 less than the second distance, and thence upwardly a fourth distance L_4 substantially greater than the third distance L_3 to a third transverse joint 58.

As is preferred, the first and third dimensions, L_1 and L_3 , are equal to each other, and the second and fourth dimensions, L_2 and L_4 , are equal to substantially four times that value.

As can be seen in FIG. 2, in a preferred embodiment the series of compartments defined by the looped inner side wall 24 extends throughout substantially the full length of the bag.

Referring to FIGS. 1-3, preferably the outer side walls 20 and 22 are joined, e.g. at joint 62, into a continuous loop, the joint 62 spaced from the ends so that the ends merely comprise narrow end folds 63, 64. Preferably, as shown, the joint defines a pocket 71, in which is enclosed a horizontal hanger bar 70, engaging the inside of top fold 64, with a hook 72, for engaging a closet rod, protruding from the mid point.

Preferably, the walls 20, 22, 24 are each formed of transparent plastic film, for example a window clear .004 inch thick vinyl plastic, in many instances such construction enabling the user to see, from one side of the bag, the entire contents of the bag, despite the fact that some of the articles lie in compartments on the opposite side of the inner side wall member.

Preferably, for plastic construction, the strapping member system as shown in FIGS. 6-9 is employed. Referring to FIG. 6, the vertical edge 36 of the bag at which access to the compartments is to be had is preferably provided with a zipper. For this purpose the corresponding vertical edges of the outer walls 20 and 22 are provided with vertical strapping members 42 and 44, bent about the vertical edges, and zipper support cloth members 38 and 40 have their margins secured face to face with the walls as shown, the strapping members 42 and 44 being bent about both, and secured, preferably by stitching as shown. The corresponding vertical edge of the inner side wall 24 is offset as shown in FIG. 6 so as to be clear of the zipper 46 when it is closed. The edge of this inner side wall 24 is similarly provided with a vertical strapping member 55 which is bent about the edge and secured, preferably by stitching as shown.

Referring to FIGS. 7 and 9, the inner side wall 24 is secured at a transverse joint 26 to the outer side wall 20 by means of inner strapping member 50 and outer strapping member 52, the former disposed on the side of the inner side wall directed away from the outer side wall 20 to which it is secured, and the other strapping member 52 disposed on the outside surface of the outer side wall

20, as shown. The two strapping members 50 and 52, and the intervening side wall members 20 and 24 are secured together, preferably by stitching as shown.

Referring to FIG. 7, the transversely extending strapping members 50 and 52 extend beyond the vertical edge of inner side wall 24 and its vertical strapping member 55, and the ends thereof are secured, along with the margin of outer side wall 20 and the zipper cloth 38, within the vertical strapping member 42.

Referring to FIG. 8, the vertical edge 34 of the bag is permanently closed, margins of the side walls 20, 22 and 24 being disposed within the confines of vertical strapping member 48 bent thereabouts and secured, preferably by stitching. As seen in FIG. 2, the cross-section of FIG. 8 is taken through the bottom of one of the loops in the inner side wall 24, and, accordingly, three layers of the inner side wall 24 are secured at the closed edge 34 of the bag. The ends of the horizontal strapping members are secured with vertical strapping member 48, similar to the manner shown for the opposite edge in FIG. 7.

Referring to FIG. 9 it will be seen that a series of compartments, A, B, C and D are defined by the loops of the inner side wall 24, secured by outer strapping members 52, 54 and 58, and inner strapping members 50, 56 and 60 as described above.

In FIG. 9 the bag is shown in a substantially relaxed state, without contents, though sufficiently distended in order to show the relationship of the various components. It will be seen, that due to the specified dimensions of the various portions of the loops, the compartments overlap each other, and the loops of the inner side wall at both top and bottom of each compartment provide for substantial adjustment of the dimensions of the compartments without influence upon the form of the outer side wall members, though of course they can be flexed also.

Referring to FIG. 10 an article of substantial vertical dimension is inserted in compartment A, substantially filling the entire space between the inner and outer side walls 20 and 22. The article is substantially taller than the compartment in its relaxed state, accordingly the loop defining the top of the compartment is distended upwardly, rather than in the normal downward drooping relationship. Accordingly compartment B as well as compartment C, is altered substantially in form, but in compartment D another article identical to the article inserted in compartment A, can be inserted.

Referring to FIG. 11 an article is inserted in compartment A having only substantially one-half the thickness of the overall thickness of the bag, and identical articles are inserted in compartment B, C and D, the inner side wall 24 between successive joints, e.g. joints 28 and 30, assuming an S shaped configuration with a substantially straight vertical run in the mid portion.

Referring to FIG. 12, identical articles are again inserted in the compartments A, B, C and D, but of lesser vertical extent, with the unique result that from one side of the bag, e.g. through outer wall 20, every article within the bag can be seen, as indicated by the horizontal arrows, despite the fact that certain of the articles e.g. the contents of compartments B and D, lie on the opposite side of the bag.

Referring to FIG. 13, the fact that the outer side wall 20 and 22 can be laterally distended is illustrated, here defining triangular compartments of substantial volume.

From consideration of FIGS. 9 through 13 it will be obvious that numerous articles of widely different shapes can be inserted in various compartments within the same bag, the bag adjusting to the form of the particular articles.

Among the numerous possible uses of the bag are the dust free storage of handbags and shoes, the moth-proof storage of small woolen items such as mittens, hats and scarves, as well as of sweaters and larger woolens, and the storage of men's shirts.

What is claimed is:

1. In an elongated wardrobe bag of the type formed of flexible web material, providing a multiplicity of vertically spaced apart compartments accessible from a vertical edge of the bag, said bag having means adapted to support said bag, the improvement wherein said bag comprises the combination of two outer side wall members of flexible web material each extending along the length of said bag and an inner side wall member extending at least along a portion of the length of said outer side wall members, said inner side wall member having a running length substantially longer than the corresponding running length of said outer side wall members, said inner side wall member being configured into a multiplicity of vertically spaced apart special loops, and said inner side wall member secured to said outer side wall members alternatively between said loops by transversely extending joints, said inner side wall member at least extending freely from a first transverse joint with one of said outer side wall members, downwardly a first distance, thence upwardly a second distance substantially greater than said first distance to a second transverse joint with the other of said outer side wall members, thence freely downwardly a third distance less than said second distance, thence upwardly a fourth distance substantially greater than said third distance to a third transverse joint, the running length of inner side wall from said first to said third joints and the length of outer side wall between said first and third joints defining a first compartment, the portion of said inner side wall member extending between said second and third transverse joints forming the bottom of the next above compartment, and said compartments caused to vertically overlap due to said relationship of said third and fourth distances.

2. The wardrobe bag of claim 1 wherein said third distance is substantially less than the difference between said first and second distances.

3. The wardrobe bag of claim 1 wherein said first and third distances are equal substantially to the same value, and said second and fourth distances are equal substantially to four times said value.

4. The wardrobe bag of claim 1 wherein said inner side wall member extends substantially above said third joint, and defines a series of loops like those between said first and third joints.

5. The wardrobe bag of claim 1 where said inner side wall member is secured to both of said outer side wall members in a vertical, permanently closed joint extending at least substantially continuously throughout the extent of said inner side wall member, said joint located at one of the vertical edges of said bag, the interior of the compartments formed by said inner side wall member accessible only from the opposite vertical edge of said bag.

6. The wardrobe bag of claim 1 wherein said inner and outer side wall members are formed of plastic film, the vertical edges of all of said wall members secured to vertical reinforcing strapping members, and said transverse joints each comprising two transverse strapping members, one on the outside of the respective outer side wall member, the other on the side of said inner side wall member directed away from said respective outer side wall member, securing means joining together said two transverse strapping members and the intervening inner and outer side wall members, said transverse strapping members, at their ends, secured to the vertical strapping members of said respective outer side wall member.

7. The wardrobe of claim 6 wherein, at one vertical edge of said bag, all three side members are joined together by a vertical strapping member, folded, on the outside, over outside margin portions of said two outer side wall members, each side wall member having its own vertical strapping member at the opposite vertical edge, except at said transverse joints said last mentioned vertical edge of said inner said wall member being free of said outer side wall members.

8. The wardrobe bag of claim 7 having an elongated zipper adapted to close said bag at said opposite vertical edge, said zipper having two elongated cooperating zipper members wherein each of said elongated zipper members is joined to one of the outer side wall members and its vertical strapping member along said opposite vertical edge, the corresponding edge of said inner side wall member located inwardly thereof.

9. The wardrobe bag of claim 1 adapted to hang side by side with clothes hanging from hangers on a rod, and to occupy no more space in said closet than required by contents in said bag, wherein said two outer side wall members are joined together by joining means to form an endless loop, the location of said joining means spaced from the ends of said bag, whereby the ends of said bag are formed by end folds of continuous side wall material.
